UNITED STATES PATENT OFFICE.

CHARLES EDWARD JEWETT, OF NORTH ANDOVER, MASSACHUSETTS.

BUR-CONVEYER ATTACHMENT FOR WOOL-CARDS.

1,351,653.

Specification of Letters Patent. Patented Aug. 31, 1920.

Application filed March 22, 1919. Serial No. 284,292.

To all whom it may concern:

Be it known that I, CHARLES E. JEWETT, a citizen of the United States, residing at North Andover, in the county of Essex and 5 State of Massachusetts, have invented certain new and useful improvements in Bur-Conveyer Attachments for Wool-Cards, of which the following is a specification.

This invention relates to machines for 10 carding wool. It is more particularly useful as an attachment for what are known as worsted cards. In the operation of worsted cards and other cards having revoluble carding rolls, such as doffers and strippers, it is 15 desirable to remove what are known as burs and other material which should not go into the yarn.

One method of removing burs is by the 20 use of what are known as bur rolls, which usually have radial blades and which revolve in such a direction and in such proximity to the card rolls as to beat burs out from the fiber. Flat sheet metal pans are usually used to catch such burs. Such pans are 25 supposed to be cleaned at regular intervals manually by the operator. If the operator forgets such cleaning, the burs and other waste pile up and after a time are sucked in or fall into the fleece and cause bunches in 30 the roving and yarn.

Many attempts have been made to not 35 only catch but to automatically carry away such burs and waste from the card, such as by conveyer belts, air blasts, etc., but on account of the peculiar oily and gritty character of the material, peculiar difficulties must be overcome.

Not only for this reason but because a 40 card, especially a worsted card, is a complicated machine the rolls of which must be removed from time to time for stripping and grinding, any device for the purpose intended must be arranged so as not to be in the way and so as to be capable of removal 45 with little difficulty.

The purpose of my invention is to provide a positive-action, simple, compact device, which is easily removable and which will not be in the way of the proper operation 50 of the machine.

In the drawings, Figure 1 is a partly dia- 55 grammatic plan view of part of a worsted card of well known type equipped with my attachment. Fig. 2 is an elevation of Fig. 1 looking at the driving end of my attachment, some parts being broken away to

show other parts beyond. Fig. 3 is an enlarged, perspective view of a bracket and bearing at the driving end of my attachment. Fig. 4 is an enlarged elevation of Fig. 1 looking in the direction of the arrow. Fig. 5 is an enlarged plan view of one form of screw conveyer. Fig. 6 is a similar plan view of another form of conveyer, and Fig. 7 is a fragmentary view of still another form of conveyer. Fig. 8 is an enlarged end view of my preferred form of bearing for the delivery end. Fig. 9 is a detail.

In the drawings, A represents the frame of a worsted card. C and B are carding rolls, shown as lickerin and divider, and D and E are revoluble bur rolls having radial beater blades, all of well known type.

The drawing indicates a card having two bur rolls, but I may use my attachment on cards having one or more such bur rolls.

Instead of a flat pan, I provide for each bur roll a substantially U-shaped trough, such as F or G, which extends across the card proximate the bur roll in position to receive the burs knocked out by it.

What I will call the driving end of the trough at 8 or 9 may be closed or open, preferably open. The opposite or delivery end 11 or 21 preferably extends beyond the other side of the card so that it can deliver into a spout, such as 13 or 23, under which a basket L or box can be placed. A single basket can receive the material from both troughs. Extending through each trough F or G I locate a revoluble screw conveyer, such as H or K.

As shown in Figs. 1, 2, 3, 4 and 5, each conveyer consists substantially of a central shaft 14 which extends through the trough and beyond it at the driving end and which carries a thread 15, preferably of a flat cross section. At its driving end each shaft is carried in a bearing 16 which, by a bolt 17, is fastened to a bracket such as 18.

In Fig. 4, I show the delivery ends of my screw conveyers H and K supported in different ways. K is carried in bearing 26 detachably attached to bracket 28 by a bolt 27, while H, as shown in detail in Fig. 8, rests in a V-shaped or U-shaped open bearing member 36, clearly shown in Fig. 8, attached to the inside of trough G near its delivery end 11 and to a suitable bracket or stand 38 by bolt 39.

Into this open bearing the outside of the screw thread 15 fits revolubly. I find that

such an open bearing keeps the delivery end steady and does not obstruct the delivery of the material.

For driving means, I use sprockets 30 carried by H, 31 carried by K and 32 carried by the slow-running lickerin roll C. These are shown as connected together by endless chain 33, which is preferably provided with a suitable hook 34 whereby it can be disconnected.

When it is desired to remove my conveyers H and K, it is necessary only to unhook 34, remove chain 33, remove the bearing bolts, such as 17 and 27, then lift out screw conveyers and bearings. The troughs can be readily attached to brackets by any suitable means and can readily be removed as the conveyers are removed.

It is manifest that any other suitable driving means for the screw conveyers may be used, but I prefer to have them driven at a relatively slow speed from any of the slow running card rolls.

In Fig. 5, I show my preferred form of screw conveyer having a shaft or core 14 and flat thread 15. I may, however, use the construction shown in Fig. 6, wherein the core 44 is of sufficient length only to form the bearing, while the flat thread 45 is open the rest of its length. I may use also a screw conveyer of the cork-screw type, such as shown in Fig. 7, having a short core or bearing 54 and a round thread 55.

I prefer to use a metallic trough and a metallic screw conveyer, as the peculiar oily and gritty character of burs quickly give them an excellent polish whereby there is little frictional resistance and the burs are readily carried along and delivered. Each screw conveyer is preferably driven at a slow speed so as to crawl.

I prefer to arrange the troughs and screw conveyers so that by unloosening a few bolts or screws they can be readily lifted out or, in the case of the conveyer, so that by removing a collar, such as 19, it can be pulled out of its bearing and removed.

I find, that in order to overcome the tendency of burs from some grades of wool to cling to the screw conveyer and to be carried around thereby without advancing, it is desirable to introduce a resistance member attached lengthwise of the trough. In connection with trough G, as shown in Figs. 1 and 8, such a resistance member 47 is shown as a strip which may be of wood, metal or other suitable material, attached to trough G and extending lengthwise thereon. This should be on the side of the screw conveyer opposite from the bur roll, but might be on either side, and may extend the full length of the conveyer or, preferably, part of its length. This resistance member overcomes any tendency of the stock to re-

volve with the conveyer, and causes it to move steadily toward the delivery end of the trough.

As shown in Fig. 9, this resistance member may be, instead of a strip, a series of pins or teeth which rake toward the delivery end and which may conveniently be made of Garnett wire 57, as shown.

I claim:

1. The combination in a card having revoluble carding rolls and a revoluble bur roll for beating burs from one of such rolls, of a metallic trough having an open end and extending across such card proximate said bur roll in position to receive the burs, and a revoluble metallic screw conveyer which extends through such trough and rests at its open end therein adapted to convey burs through the trough and to deliver them from the open end thereof, bearings which carry the other end of the screw conveyer, and driving means for said conveyer proximate said bearings which connect it with a relatively slow moving part of said card.

2. The combination in a card having revoluble carding rolls and a revoluble bur roll for beating burs from one of such rolls, of a trough having an open end and extending across such card proximate said bur roll in position to receive the burs, and a revoluble screw conveyer which extends through such trough and rests at its open end therein adapted to convey burs through the trough and to deliver them from the open end thereof, bearings which carry the other end of the screw conveyer, and driving means for said conveyer proximate said bearings.

3. The combination in a card having revoluble carding rolls and a revoluble bur roll for beating burs from one of such rolls, of a U-shaped trough having an open end and extending across such card proximate said bur roll in position to receive the burs, and a revoluble screw conveyer which extends through such trough adapted to convey burs through the trough and to deliver them from the open end thereof.

4. The combination in a card having revoluble carding rolls and a revoluble bur roll for beating burs from one of such rolls, of a trough having an open end and extending across such card proximate said bur roll in position to receive the burs, and a revoluble screw conveyer which extends through such trough adapted to convey burs through the trough and to deliver them from the open end thereof.

5. The combination in a card having revoluble carding rolls and a revoluble bur roll for beating burs from one of such rolls, of a trough extending across such card proximate said bur roll in position to receive the burs, and a revoluble screw conveyer which

extends through such trough adapted to convey burs through the trough.

6. The combination in a worsted card having revoluble carding rolls and one or more 5 revoluble bur rolls for beating the burs from such rolls, of troughs each extending across such card approximate a bur roll in position to receive the burs therefrom, and revoluble screw conveyers each of which ex-

10 tends through one of such troughs and is adapted to convey burs therethrough, together with one or more spouts, one at the delivery end of each trough as described.

7. The combination in a card having revoluble carding rolls and a revoluble bur roll 15 for beating burs from one of such rolls, of a trough having an open end and extending across such card proximate said bur roll in position to receive the burs, and a revoluble screw conveyer which extends through such trough adapted to convey burs through the trough and to deliver them from the open 20 end thereof, together with a resistance member which extends lengthwise of such trough.

25 8. The combination in a card having revoluble carding rolls and a revoluble bur roll for beating burs from one of such rolls, of a trough having an open end with a V-shaped open bearing therein and extending 30 across such card proximate said bur roll in position to receive the burs, and a revoluble screw conveyer which extends through such trough, one end resting on such open bearing adapted to convey burs through the 35 trough and to deliver them from the open

end thereof, bearings which carry the other end of the screw conveyer, driving means for said conveyer proximate said bearings, and a resistance member attached lengthwise to said trough proximate the screw conveyer.

40 9. The combination in a card having revoluble carding rolls and a revoluble bur roll for beating burs from one of such rolls, of a trough having an open end and extending 45 across such card proximate said bur roll in position to receive the burs, and a revoluble screw conveyer having an open thread which extends through such trough adapted to convey burs through the trough and to deliver 50 them from the open end thereof, together with a resistance member which extends lengthwise of such trough.

55 10. The combination in a card having revoluble carding rolls and a revoluble bur roll for beating burs from one of such rolls, of a trough having an open end and extending 60 across such card proximate said bur roll in position to receive the burs, and a revoluble screw conveyer having an open thread which extends through such trough adapted to convey burs through the trough and to deliver 65 them from the open end thereof, together with a resistance member having a series of teeth which rake toward the open end of the trough and which extends lengthwise of such trough.

In testimony whereof I have affixed my signature.

CHARLES EDWARD JEWETT.
